UNITED STATES PATENT OFFICE.

WILLIAM A. HUELDONK, OF LE GRAND, CALIFORNIA.

CONCENTRATING-TABLE.

1,104,300.

Specification of Letters Patent. Patented July 21, 1914.

Original application filed January 23, 1913, Serial No. 743,783. Divided and this application filed June 23, 1913. Serial No. 775,190.

To all whom it may concern:

Be it known that I, WILLIAM A. HUELDONK, a citizen of the United States, residing at Le Grand, in the county of Merced, 5 State of California, have invented certain new and useful Improvements in Concentrating Tables; and I do declare the following to be a clear, full, and exact description of the same, such as will enable others 10 skilled in the art to which it appertains to make and use the same, reference being had to the accompanying drawings and to the characters of reference marked thereon, which form a part of this application.

15 This invention relates to improvements in concentrating tables and is the type of table shown in my application for patent filed January 23rd, 1913, Ser. No. 743,783, of which this case is a divisional part.

20 The object of the invention is to produce a concentrating table for use in a concentrating mechanism, which table is especially designed for use beneath a longitudinal distributing trough from which the water and 25 mineral to be concentrated come in properly proportioned amounts. The concentrating table is provided with a longitudinal screen on which the material drops from the distributing trough. Said screen prevents 30 splashing and from such screen the material passes off on each side of the same onto the table proper.

A further object of the invention is to produce a simple and inexpensive device and 35 yet one which will be exceedingly effective for the purposes for which it is designed.

These objects, I accomplish by means of such structure and relative arrangement of the parts as will fully appear by a perusal 40 of the following specification and claim.

On the drawings similar characters of reference indicate corresponding parts in the several views.

Figure 1 is an end view of the complete 45 table. Fig. 2 is a top plan view of the same.

Referring now more particularly to the characters of reference on the drawings, the numeral 1 designates the distributing trough which may of course be of any suitable type. 50 The concentrating table proper consists of a longitudinally disposed member 2 positioned directly under the distributing trough 1 to first receive the material therefrom and said member 2 is provided with a

wire mesh or screen 3 of suitable size to 55 prevent splashing of water and material.

It is a well known fact that in order to receive the best results in the concentrating of pulp, slime or fine sand, it is necessary to maintain the same as nearly unagitated as 60 possible during the delivering of the same to the concentrating device in order that the very fine gold may remain as near the bottom of the material as possible so it can be caught and held as the material passes over 65 the concentrating table. It is therefore the function of the raised central member 2 with the screen thereon, to catch the material as it comes from the delivering means and then, by reason of the mesh of the 70 screen, it will be held for a moment in suspension before it flows over the sides of the elevated member onto the concentrating table proper. This moment of suspension allows it to settle and become unagitated 75 prior to its passing onto the concentrating table and further the mesh of the screen tends to prevent any splashing of the water or material from the elevated member onto the concentrating table, as above noted. 80

The special function of having the central member 2 raised above the level of the concentrating table proper is as follows: The concentrating table here shown is designed especially for use on gold dredgers where 85 the table may not be at all times perfectly level, that is, it may be at different angles according to the position the dredger assumes. Under these conditions such raised central portion prevents the material which 90 has fallen on one side of the table from thereafter crowding over and passing back to the other side of the table which it would do if the table tilted at an angle and such central portion was not there. A still further object of said central raised portion 2 is to provide a little fall for the pulp after 95 it strikes the screen and separates, in which fall the gold falls the fastest and will nearly always slide directly down the sides of the elevated portion 2, thus bringing it directly on the table from which it will not raise again, whereby it is more easily recovered from the slime. From said screen the material falls over on each side of said central 100 member 2 onto the riffles or corrugations 4 which are disposed in a slightly sloping manner from said member 2 to the outer 105

edges of the table where the overflow passes into troughs 5 having discharge outlets 6 adapted to lead to the tailing pile. The forward end of the table is provided with 5 chutes 7 over which the concentrates discharge into a suitable receptacle. The riffles 4 of course catch and discharge the precious metals and the concentrates at the end and over the chutes 7 in the usual manner. These riffles may be of any usual make. 10 The table may be vibrated in any desired manner.

From the foregoing description it will be readily seen that I have produced such a device as substantially fulfills the objects of the 15 invention as set forth herein.

While this specification sets forth in detail the present and preferred construction of the device, still in practice, such deviations from such detail may be resorted to as 20

do not form a departure from the spirit of the invention.

Having thus described my invention what I claim as new and useful and desire to secure by Letters Patent is:—

25 A concentrating table consisting of a central longitudinal member, a screen mesh disposed on said central member, a platform disposed in a sloping manner on each side of said central member, and in a lower plane 30 than said central member, each of said platforms being provided with a plurality of riffles, as described.

In testimony whereof I affix my signature in presence of two witnesses.

WILLIAM A. HUELDONK.
